UNITED STATES PATENT OFFICE

100,589

DESIGN FOR A CHILD'S SWING

Dean Tinker, Columbus, Ohio

Application May 18, 1936, Serial No. 62,696

Term of patent 7 years

To all whom it may concern:

Be it known that I, Dean Tinker, a citizen of the United States, residing at Columbus, in the county of Franklin and State of Ohio, have invented a new, original, and ornamental Design for a Child's Swing, of which the following is a specification, reference being had to the accompanying drawing, forming a part thereof.

Fig. 1 is a perspective view of the child's swing showing my new design ;

Fig. 2 is a top plan view.

I claim:

The ornamental design for a child's swing, as shown.

DEAN TINKER.
